[57] CLAIM

The ornamental design for a storage basket cart, as shown and described.

DESCRIPTION

FIG. 1 is a front elevational view of a storage basket
cart showing my new design;

FIG. 2 is a rear elevational view;

FIG. 3 is a right side elevational view;

FIG. 4 is a top plan view; and

FIG. 5 is a bottom plan view thereof.

The left side elevational view is the mirror image of the right side elevational view.
